ADJUSTING DEVICE FOR LAPPING TOOLS

Alden M. Drake, West Hartford, Conn., assignor
to Niles-Bement-Pond Company, West Hartford, Conn., a corporation of New Jersey

Application November 18, 1944, Serial No. 564,155

6 Claims. (Cl. 51—184.3)

1

This invention relates to lapping machines and particularly to a machine for lapping internal cylindrical surfaces to precision dimensions.

An object of the invention is to provide improved lap adjusting means in a machine for automatically actuating a work piece being lapped over the surface of a lapping tool which may be rotated simultaneously with reciprocations of the work piece.

Primarily it is an object of the present invention to provide impact means manually applied under controllable conditions to slightly vary the effective diameter of the lapping tool during the lapping operation.

A feature of importance is that the impact means are operative in one direction to increase the effective diameter of the lapping surface and in the opposite direction to decrease the effective diameter.

Another feature of advantage is that the two impact means are independently actuated and may be adjusted individually over wide ranges, so that but one or both impact means may be employed to any extent that may be necessary to make the desired adjustment.

With the above and other objects in view the invention includes the features of construction and operation set forth in the following specification and illustrated in the accompanying drawings.

In the accompanying drawings annexed hereto and forming a part of this specification, I have shown the invention embodied in a hole lapping machine for rolls of small size used in dimension gages but it will be understood that the invention can be otherwise embodied and that the drawings are not to be construed as defining or limiting the scope of the invention, the claims appended to this specification being relied upon for that purpose.

In the drawings:

Figure 1 is a vertical sectional view taken longitudinally through the principal parts of a machine embodying one form of the present invention.

Fig. 2 is a longitudinal sectional view in elevation showing one form of impact means for forcing a lap axially along its arbor to slightly increase the size of the lapping surface during the lapping operation.

Fig. 3 is a detail view of parts shown in Fig. 2 taken from below.

Fig. 4 is a longitudinal view of a lap on its

2

arbor showing one of the impact members in retracted position.

Fig. 5 is a cross sectional view of the arbor and lap taken on the plane of line 5—5 of Fig. 4.

Fig. 6 is a longitudinal view partly in section of another form of impact means.

Fig. 7 is an end elevation of the impact means shown in Fig. 6.

Fig. 8 is a longitudinal sectional view of a part of the mechanism shown in Fig. 6, the section being taken on the plane of line 8—8 in Fig. 6.

Fig. 9 is a horizontal sectional view of parts shown in Fig. 6, the section being taken on the plane of line 9—9 in Fig. 6.

15 Fig. 10 is a sectional view of a part of the impact mechanism for reducing the size of the lapping member, the section being taken on the plane of line 10—10 in Fig. 7, and

Fig. 11 is a sectional view of parts shown in Fig. 20 7, the section being taken on the plane of line 11—11 in Fig. 10.

In the above mentioned drawings there have been shown two embodiments of the invention which are now deemed preferable, but it is to be understood that changes and modifications may be made within the scope of the appended claims without departing from the spirit of the invention.

30 In lapping rotatably mounted members for gages it is essential that the holes by means of which they are mounted be of uniform diameter from end to end and without bell-mounting. The rolls must fit their arbors closely and evenly from 35 end to end so that they will not tilt during use but will rotate smoothly on their arbors about a fixed axis. Heretofore precision lapping of internal cylindrical surfaces has, for the most part, been done manually, the work piece being held manually in position upon a rotating lapping tool on a suitable spindle and slowly reciprocated back and forth during rotation of the spindle and lapping tool. The lap usually comprised a split cast iron sleeve charged with abrasive and 40 fitting tightly but resiliently over a slightly tapered arbor secured to the spindle. To expand the lapping surface the sleeve having the lapping surface was forced axially along the tapered arbor.

45 The present invention relates particularly to impact means for forcing the expandable lap predetermined slight amounts axially during the lapping operation to slightly increase its diameter, other impact means also being provided to move the lapping tool in the opposite direction

on its arbor to reduce slightly its lapping diameter.

Briefly, and in its preferred aspect, the invention may include the following principal parts: First, a spindle adapted to be rotated by any appropriate means and having means at its forward end to mount an arbor extending axially from the spindle; second, a plunger aligned with the lapping spindle and adapted to be resiliently retracted and released for forward movement to strike the end of the lapping tool so that the position of the lapping tool on its spindle may be adjusted axially to slightly increase its diameter; and third, a second plunger mounted for rapid forward movement and adapted to engage a member bearing against the opposite end of the lapping tool and move it axially to slightly decrease its diameter.

Referring more in detail to the figures of the drawings and first to Fig. 1, I provide a spindle 10 adapted to be driven by a bevel gear 11 on a short shaft 12 in alignment with the spindle 10 and which in turn may be driven through any suitable connections such as a driving bevel gear 13 connected by means not shown to a suitable source of power. At the forward end of the spindle is an arbor 19 extending axially therefrom and preferably detachably mounted thereon.

Above the spindle 10 is a reciprocated member 14 on which is mounted a work holder 31 within which the work piece being lapped is mounted for reciprocatory movement along the arbor 19 during the lapping operation.

The above members are or may be similar in every way to corresponding members in my co-pending application Serial No. 520,257, filed January 29, 1944, of which the present application is a continuation in part.

The lapping member 20 may be similar to the member shown in the above referred to application and formed of cast iron or other metal slotted longitudinally throughout its length and bored to fit a slight tapered portion of the arbor 19.

In order to adjust the position of the lapping member or sleeve 20 upon its arbor 19 to vary its effective diameter as required during the lapping operation, impact means are provided which may be actuated manually to deliver a carefully regulated blow upon an end face of the split sleeve forming the lapping tool 20 to force this member axially on its arbor 19 a slight but predetermined distance depending upon the force of the blow. Figs. 1, 2 and 3 show one form of impact mechanism acting in one direction only to increase the diameter of the lapping surface of the lapping tool. To effect this impact adjustment of the lap 20, a bracket 21 is mounted upon the base of the machine having a plunger 22 therein disposed accurately in alignment with the spindle 10 and arbor 19. This plunger 22 is mounted within the retractile member 23 within the bracket 21 and is normally forced toward the lapping spindle by a helical spring 24. Manually retracting this member 23 compresses the spring 24, then, upon release of the member 23 the plunger 22 will be forced forwardly and its end face will be brought into contact with and force the lapping tool 20 axially along its arbor 19. To adjust the axial position of the plunger 22 so that its end face will strike the end of lapping sleeve 20, the plunger 22 may be threaded throughout the major portion of its length, the threads of which engage a retractile detent 25 mounted within the bracket 21. The plunger

22 may, therefore, by rotation, be accurately adjusted so that when forced forward it will strike the lap 20. Also, by disengaging the detent 25, the plunger 22 may be quickly moved any distance in either direction. The forward or striking end of this plunger 22 may be provided with an adapter 26 rotatable within the plunger 22 and recessed to fit over the end of the lapping arbor 19 and directly engage the front face of the sleeve 20 forming the lap.

In order to control the force of the blow effected by this plunger 22, means are provided to adjust the pressure of the helical spring 24. As will be seen in Fig. 2, the helical spring is housed in the bracket 21 within a suitable recess. The forward end of the spring 24 bears against the head of a bolt 27 extending through the bracket 21 and through a portion of the retractile member 23. The outer end of this bolt 27 is threaded and is engaged by a suitable manual adjusting nut 28. By rotation of this nut 28 the pressure of the helical spring 24 forcing the retractile member 23 toward its forward position may be widely varied. In order to effect the delivery of the blow by plunger 22 against the end face of lap 20 a hand lever 29 is provided having a projection or latch 30 adapted to engage a depending portion of the retractile member 23 so that by oscillation of this handle 29 the projection will be disengaged from the depending portion of the retractile member 23 after a predetermined retractile movement. This will release the retractile member 23 for forward movement under the adjusted pressure of the helical spring 24. To adjust the plunger 22 so that it will contact the end face of the lapping tool and advance this tool a predetermined distance when released, it is only necessary to rotate the plunger 22 within the retractile member 23.

Figs. 6 to 11 show another form of impact means for action upon the lapping member 20 to move it axially along its arbor in either direction to increase or decrease the effective diameter of its lapping surface.

In the mechanism shown in Fig. 6 et seq. for advancing the lap 20 in a direction to increase its effective diameter, a construction very similar to that shown in Fig. 2 is employed. This mechanism has a retractile plunger 32 which may be adjusted axially toward or from the lapping tool 20 by means of a threaded portion thereon and the impact may be adjusted by a helical spring 34 adjusted by a manually rotatable nut 35. The blow may be delivered by depressing a plunger 36 to release a latch 37 from a member 39 within which the plunger 32 is mounted attached to the plunger 32 to force the plunger toward the lap. The above described mechanism is mounted on a fixed bracket 38 and will be clear by an examination of Figs. 6, 7 and 8.

In order to deliver a blow in a direction to move the lapping tool 20 along its arbor 19 in a direction to reduce its effective diameter, the following mechanism is employed. Within the bracket 38 supporting the plunger 32 for increasing the diameter of the lap is a second plunger 40 which may be retracted manually against the pressure of a coil spring 41 and released by simply releasing the handle. The pressure effected by the spring 41 may be regulated by a threaded nut 42, rotation of which varies the compression of the spring 41 to any predetermined degree. The inner or active end of the plunger 40 is within striking distance of an

arm 43 pivoted substantially at its central position on a horizontal axis 44 so that it may swing in a vertical plane. The plunger 40 strikes the lower end of this vertical pivotal arm 43 and at its upper end is provided with a member 45 adapted to strike against an abutment member 46 engaging against the inner end face of the sleeve 20 forming the lapping tool. A spring 47, as shown in Figs. 7, 10 and 11, serves to retain the arm 43 in its vertical striking position and a pendulum 48 supported within a horizontal bearing in the bracket 38 at the upper portion of the arm 43 serves to hold in vertical position the head 45 engageable against the striking member 46 when the arm 43 is oscillated by the plunger 40.

What I claim is:

1. An adjusting device for lapping tools of the expansible sleeve type, said device comprising a striking plunger mounted in alinement with said sleeve and movable into contact with an end face of said sleeve while mounted on its spindle, means normally forcing said plunger in one direction, retracting means for said plunger, and means to release said plunger from a retracted 25 position, whereby said plunger may strike and force said sleeve axially on its spindle.

2. An adjusting device for lapping tools of the expansible sleeve type, said device comprising a striking plunger mounted in alinement with said sleeve and movable into contact with an end face of said sleeve while mounted on its spindle, means normally forcing said plunger in one direction, retracting means for said plunger, and means to release said retracting means from a predetermined retracted position, whereby said plunger may strike a regulatable blow and force said sleeve axially on its spindle.

3. An adjusting device for lapping tools of the expansible sleeve type, said device comprising a striking plunger mounted in alinement with said sleeve and movable into contact with an end face of said sleeve while mounted on its spindle, means normally forcing said plunger toward its striking position, retracting means for said plunger, and means to release said retracting means from a predetermined retracted position

whereby said plunger may strike and force said sleeve axially on its spindle.

4. An adjusting device for lapping tools of the expansible sleeve type, said device comprising a striking plunger mounted in alinement with said sleeve and movable into contact with an end face of said sleeve while mounted on its spindle, means normally forcing said plunger in one direction, retracting means for said plunger, means to adjust the plunger axially relative to its retracting means, and means to release said retracting means from a predetermined retracted position whereby said plunger may strike and force said sleeve axially on its spindle.

5. An adjusting device for lapping tools of the expansible sleeve type, said device comprising a striking plunger mounted in alinement with said sleeve and movable into contact with an end face of said sleeve while mounted on its spindle, and a second plunger mounted parallelly to said first plunger to actuate a pivotal arm into position to strike the sleeve at its opposite end, means normally forcing said plungers in one direction, separate retracting means for said plungers, and means to individually release said retracting means from predetermined retracted positions whereby said plungers may force said sleeve axially on its spindle in either direction.

6. An adjusting device for lapping tools of the expansible sleeve type, said device comprising parallel striking plungers, one of which is mounted in alinement with said sleeve and movable respectively into contact with an end face of said sleeve while mounted on its spindle, means normally forcing said plungers in one direction, individual retracting means for said plungers, and means to release one of said retracting means from a retracted position whereby its plunger may strike and force said sleeve axially on its spindle in a direction to enlarge the diameter of said sleeve, and means to release the other of said retracting means from a retracted position and force its plunger in a direction to engage a striker and oscillate said striker against the opposite end of said sleeve.

ALDEN M. DRAKE.
